DEGENERATIVE AUDIO DETECTOR
CIRCUITSeymour Hunt, Jackson Heights, N. Y., assignor
to Radio Corporation of America, a corpora-
tion of Delaware

Application October 8, 1938, Serial No. 233,906

4 Claims. (Cl. 250—20)

My present invention relates to substantially linear detector circuits which are capable of delivering detected energy in amplified form, and more particularly to detectors of the plate rectification type utilizing inverse audio feedback in order to secure a substantially linear detection characteristic.

The so-called "infinite impedance" detector is well known in the art, and is in reality a biased detector utilizing plate circuit rectification and employing an unbypassed load impedance in the cathode circuit. Such a detector network functions in the manner of a diode circuit; the audio voltages developed across its cathode load resistor are in the correct phase to cause the detector to be degenerative solely for audio voltage. Since all the audio voltage developed across the cathode load resistor is applied to the detector input the infinite impedance detector is 100% degenerative for audio voltage. It is the degeneration, and the fact that the tube is normally biased substantially to plate current cut-off, which linearizes the normal square law characteristic of the biased detector circuit.

The load resistor in the cathode circuit of an infinite impedance diode detector network presents two disadvantages. Since the cathode load resistor is above ground by the magnitude of the load, hum at 60 cycles due to heater cathode leakage may result. Again it is difficult to obtain automatic volume control (AVC) voltage in a simple manner, since the direct current voltage drop across the cathode load resistor places a negative potential on the diode plate, assuming that an auxiliary diode plate is employed adjacent the detector cathode. Furthermore, since the detector is 100% degenerative the gain thereof is less than unity, and, hence, there is no amplification in the network.

The familiar plate rectification detector has a characteristic which is square law for small signals and becomes linear for large signals. Furthermore, the cathode thereof may be maintained at ground potential, and its grid return connected to a negative biasing potential source. Such a detector is not degenerative for the carrier, and is productive of audio amplification. By utilizing inverse audio feedback between the plate and grid circuits of such a detector tube, the detection characteristic may be made substantially linear. However, since the detector circuit is square law only for small signals it is not necessary to employ 100% feedback, and hence the audio amplification property of the biased detector tube is retained.

Accordingly it may be stated that it is one of the main objects of my present invention to provide a detector network of the biased type which utilizes plate circuit rectification; there being employed substantially 25% inverse audio feedback between the output and input circuits of the detector network to render the detection characteristic substantially linear.

Another important object of my invention is to improve generally the construction of biased detectors of the plate rectification type, by feeding back from the plate circuit to the grid circuit of the detector sufficient audio voltage in degenerative phase thereby to render the detection characteristic substantially linear over the entire signal amplitude range, and the detector further including a diode for deriving AVC bias from the carrier component in the detector output circuit.

Still other objects of my invention are to improve generally the simplicity of biased detectors of the plate rectification type, and more especially to provide detectors, with inverse audio feedback, which are not only reliable and efficient in operation, but are also economically manufactured and assembled in radio receivers.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect.

Referring to the receiving arrangement shown in the drawing, let it be assumed that there is shown therein the demodulator network, or second detector, of a superheterodyne receiver. Of course, the invention is not limited to such a receiver, since any wave transmission circuit may be employed which utilizes a demodulator. Tube 1 can be of the diode-triode type; tubes of the 6J7, 6C5, 6F8, 6Q7 or 6R7 types can be used for this purpose. The grid 2 is connected to the high potential end of input coil 6, whereas condenser 7, of 100 mmf., connects the low potential end of coil 6 to the grounded cathode 3. Any desired voltage source, such as the common voltage supply source of the system, may maintain grid 2 at a negative bias with respect to cathode 3. The letter C designates the negative terminal of the bias source, the bias being applied through a 1 megohm resistor 8. The coil 6 is fixedly resonated by condenser 9 to the operating I. F., and the

detector input circuit 6-9 can be coupled to the output circuit of a prior I. F. amplifier. The usual signal transmission tubes preceding the input circuit 6-9 have been omitted, but those skilled in the art will be aware that those comprise the usual signal collector feeding one or more radio frequency amplifiers, and the latter being followed by any type of converter stage whose I. F. output feeds one or more I. F. amplifiers.

The output plate 4, of the triode section 2-3-4 of tube 1, is connected to the subsequent audio amplifier network (not shown) through a path comprising radio frequency choke coils 10 and 11 in series with an audio coupling condenser 12, the latter having a value of approximately 0.1 mf. The audio amplifiers will feed a reproducer, such as a loudspeaker of any desired type. Shunt condensers 10' and 11', each of 100 mmf., provide with chokes 10-11 a carrier filter network to prevent I. F. carrier energy from being fed back to the detector input circuit and thus cause undesirable noises. The lead resistor 13 has a value of about 250,000 ohms; it is connected in series 25 between the positive terminal of the B supply (not shown) and the series carrier choke 11. Audio voltage is developed across load resistor 13, as well as direct current voltage by virtue of carrier rectification, and the audio voltage component of the detected signals is fed back to the detector input circuit in degenerative phase. This is accomplished by providing the path including condenser 14 and the adjustable tap 15. The feedback condenser has a magnitude of about 30 0.1 mf., and hence permits the passage of audio frequency currents. Adjustment of the tap 15 along the load resistor 13 varies the percentage of inverse feedback to the detector input circuit 6-9.

As stated heretofore, the bias applied to grid 2 is such as to operate the triode section of tube 1 as a conventional biased detector which employs plate rectification. Such a detector possesses infinite impedance since it draws no grid current. It possesses a square law detection characteristic for small amplitude signals, and the characteristic becomes linear as the signal amplitude increases. The detector cathode is at ground potential, and the detector itself is not degenerative for the carrier frequency currents. As is well known, this type of detector provides audio amplification. By utilizing the inverse audio feedback through path 15-14 the detection characteristic is made substantially linear over the entire signal amplitude range, and in addition audio amplification is secured. This is accomplished by using substantially less than 50 100% inverse feedback. Actual experimental results in the broadcast band of 550-1500 k. c. with 55 a superheterodyne receiver demonstrated that approximately 25% negative audio feedback through path 15-14 is sufficient to secure linear detection. Adjustment of the tap 15 along resistor 13 shows that as the magnitude of feedback is increased, the quality of the audio reproduction, as measured by the ear, gets better until about 60 25% feedback is attained. Increasing the feedback beyond this value produces little, or no, change in the quality of the audio reproduction. 65 It will now be clear that since the detector is only 25% degenerative, considerable audio gain is secured.

Another advantage of this circuit is the fact that the auxiliary diode anode 5 cooperates with 70 the grounded cathode 3 to provide an AVC recti-

ifier. The I. F. carrier energy appearing in the plate circuit of the detector section exists therein in amplified form, and is impressed upon the diode anode 5 through an I. F. by-pass condenser 16 which has a magnitude of approximately 100 mmf. The AVC load resistor 17 is connected between the anode 5 and ground, and the resistor may have a value of 0.5 megohm. As is well known to those skilled in the art, the AVC bias developed across resistor 17 is transmitted through lead 18, which includes the audio filter network 19, to the signal grids of one or more of the signal transmission tubes preceding the second detector. The AVC circuit functions to vary the gain of each of the controlled tubes in a 10 sense such as to maintain the carrier amplitude at the detector input circuit 6-9 substantially uniform over a wide range of signal carrier amplitude variation at the signal collector of the receiver.

Experimentation with the detector network disclosed herein further reveals that the detection characteristic desired is secured even without the use of a negative direct current potential biasing source. With the bias grid return left 25 open, and utilizing solely the inverse feedback path, it was observed that the audio output increased a noticeable amount, and approximately 30%, without affecting the fidelity of reproduction. With such an arrangement the degenerative feedback is substantially closer to 100%. It 30 may be stated that the feedback voltage apparently biases the detector tube automatically.

While I have indicated and described a system for carrying my invention into effect, it will be 35 apparent to one skilled in the art that my invention is by no means limited to the particular organization shown and described, but that many modifications may be made without departing from the scope of my invention, as set 40 forth in the appended claims.

What I claim is:

1. In a detector network, a tube including at least a cathode, control grid and plate, said cathode being at ground potential, a signal input 45 circuit connected between the grid and cathode, a resistive load connected to the plate, means for biasing the grid to render the tube operative as a plate rectification detector whose characteristic is square law for weak signals and linear for 50 strong signals, and means for feeding back in degenerative phase to the grid substantially 25% of the audio voltage developed across said load resistor thereby to linearize the square law portion of said characteristic and to secure substantial audio gain over said linear portion for strong signals.

2. In a detector network, a tube including at least a cathode, control grid and plate, said cathode being at ground potential, a signal input 60 circuit connected between the grid and cathode, a resistive load connected to the plate, means for biasing the grid to render the tube operative as a plate rectification detector whose characteristic is square law for weak signals and linear 65 for strong signals, and means for feeding back in degenerative phase to the grid substantially 25% of the audio voltage developed across said load resistor thereby to linearize the square law portion of said characteristic and to secure substantial audio gain over said linear portion for strong signals, an auxiliary anode disposed in 70 said tube adjacent said cathode to provide a diode, a second load resistor connected between the cathode and diode anode, and means for im- 75

pressing the carrier energy component in the detector plate circuit upon said diode anode.

3. In a detector network, a tube including at least a cathode, a control grid and plate, said cathode being at ground potential, a signal input circuit connected between the grid and cathode, a resistive load connected to the plate, means for biasing the grid to render the tube operative as a plate rectification detector whose characteristic is square law for weak signals and linear for strong signals, and means for feeding back in degenerative phase to the grid substantially 25% of the audio voltage developed across said load resistor thereby to linearize the square law portion of said characteristic and to secure substantial audio gain over said linear portion for strong signals, said feedback means comprising a path which includes a condenser and a tap slidable along said load resistor.
- 10 4. In combination with at least one signal

transmission tube, a detector network of the plate rectification type and including a tube having a cathode at ground potential and a signal input circuit, said detector having a detection characteristic which is square law for weak signals and linear for strong signals, a load impedance in the output circuit of the detector for developing audio voltage, and means for feeding to said detector input circuit in a degenerative phase a relatively small portion of said audio voltage thereby to linearize the square law portion of the characteristic for weak signals and to secure substantial audio gain over said linear portion, and means electrically associated with the grounded cathode and responsive to the amplified carrier component in the detector output circuit for varying the gain of said signal transmission tube.
